UNITED STATES PATENT OFFICE.

ICHITARO YOSHIDA AND KICHIGORO MATSUBAYASHI, OF OSAKA, JAPAN.

HORSESHOE.

Application filed March 10, 1922. Serial No. 542,694.

To all whom it may concern:

Be it known that we, ICHITARO YOSHIDA and KICHIGORO MATSUBAYASHI, subjects of the Emperor of Japan, both residing at 5 Osaka, Japan, have invented certain new and useful Improvements in Horseshoes; and we do hereby declare the following to be a full, clear, and exact description of the invention, such as will enable others skilled 10 in the art to which it appertains to make and use the same.

This invention relates to an improved horseshoe consisting of a U-shaped iron base member provided with a groove or channel 15 on one side, into which groove filling members or sections prepared by cutting cotton-board made of several sheets of cotton cloth piled up and pasted together with some sticky substance, are forced in closely, in 20 such a way that the face of each composing cloth of the filling sections bears parallel with the side walls of the base member, said sections being secured in the channel by fixing rods and then enamel-painted.

25 The object of this invention is to provide a horseshoe which is of light weight, elastic, and non-slipping, thereby reducing the fatigue of the horse, aiding the growth of the hoofs, and preventing noise, while the 30 shoe possesses great durability.

In the accompanying drawing, in which the similar reference numerals indicate corresponding parts throughout the several views:

35 Figure 1 is a plan view showing the ground contacting face of a horseshoe, according to this invention;

Fig. 2 is a longitudinal sectional view;

Fig. 3 is a cross-sectional view;

40 Fig. 4 is also a cross-sectional view of a slightly modified form, in which the fixing iron piece is omitted; and

Fig. 5 is a perspective view of a channel filling member.

45 Reference numeral 1 is the iron base member of the shape of an ordinary horseshoe, one side of which is flattened to contact with a hoof, while the other side is provided with a groove or channel 4 between the inner 50 and outer walls 2 and 3, and through the flat side, and on each side of the shoe is furnished a long aperture 5 provided for the securing nails. Reference numeral 6 represents the filling members composed of 55 sections, made by piling up and pasting several sheets of cotton cloth with some

waterproof viscous substance mixed with "shibu", which is the juice extracted from unripe persimmons, to form a board, and then drying and cutting the cotton board thus obtained into rectangular strips or sections a little wider than the depth of the groove or channel 4, in order to provide a tread surface beyond the walls 2 and 3, as shown in Figs. 3, 4 and 5. We apply 60 enamel-paint or other suitable substance to the inner face of the said channel or groove 4, and fill up the same closely with curved sections 6, in such manner that the edge of each section contacts with the bottom face 70 of the channel or groove 4, i. e., each strip of cloth composing a section of the filling member stands upright in the channel. Fixing rods 7 are then passed through apertures in the walls 2 and 3 of the base member 1 75 and through each of the filling sections, the ends of said rods being countersunk in the walls. The medially situated filling sections may be provided with recesses 10, the bottom of which is substantially flush with the edges of the side walls 2 and 3, see Fig. 3. These recesses are adapted to receive narrow plates of iron 9, having openings 8 in which securing nails are engaged. Said iron pieces 9 are unnecessary when flat-headed nails as shown in Fig. 4 are used. After completion of the process above mentioned, the whole surface of the filling blocks may be enamel-painted. 80

The horseshoe thus manufactured is of 85 the type in which the groove or channel 4 in the iron base member 1 is filled up closely and firmly with the filling sections 6 made of cotton cloth. The sections are fixed securely to the base member by means of rods 90 7, each strip of cloth of the filling sections bearing squarely against the bottom face of said groove or channel and projecting beyond the edges of walls 2 and 3 of the base member 1, as shown in Figs. 3 and 4. 100

This shoe has many advantages in that the contact with the ground is very soft, the fatigue of the horse is reduced to a minimum, the growth of the hoof assisted, noisy sounds are lessened, and slipping is prevented even on a slope; but the most important advantage, amongst others that might be mentioned, is the durability of the shoe, which is fully twice that of ordinary shoes. As waste cotton cloth can be utilized 105 as a material from which the filling sections are made, and as one base member can 110

be used over again by replenishing the groove or channel with new filling sections when the old ones wear out, the present horseshoe is very economical in its use, besides furnishing protection for the animal.

Having thus described the invention, what is claimed as new is:

1. A horseshoe comprising a metallic base provided with a channel on its under side, 10 a yieldable filling member deposited in said channel and extending beyond the under side of said metallic member to form a tread surface, and means for securing said yieldable member in said channel, said yieldable member being composed of a plurality of sections placed on edge tightly in said channel, the medially positioned sections being recessed below said tread surface to form 15 grooves adapted to house said securing means.
2. A horseshoe comprising a metallic base provided with a channel on its under side, a yieldable filling member deposited in said channel, and means for securing said yieldable member therein, said yieldable member being composed of a plurality of sections of thin strips of suitable material pasted to-

gether, said sections being placed on edge tightly in said channel, the sections adjacent the side walls of said channel projecting beyond the bottom edges of the walls while the medially positioned sections are substantially flush with said edges.

3. A horseshoe comprising a metallic base provided with a channel on its under side, a 35 yieldable filling member deposited in said channel and having a deeper section than the channel, and means for securing said yieldable member therein, said yieldable member being composed of a plurality of 40 sections of fabric strips pasted together, said sections being placed on edge tightly in said channel, the medially positioned sections being lower than the external ones so as to form a groove between the latter, and a 45 metal strap placed in said groove, said strap having suitable apertures registering with longitudinal slots running parallel with the sides of said metallic body for receiving nails attaching the shoe to the hoof.

In testimony whereof we affix our signatures.

ICHITARO YOSHIDA. [L.S.]
KICHIGORO MATSUBAYASHI. [L.S.]
